UNITED STATES PATENT OFFICE.

HARRY LANDRETH, OF FULLERTON, CALIFORNIA, ASSIGNOR OF FIVE-EIGHTHS TO FRED M. LUTSCHG, ONE-SIXTEENTH TO HUGH B. BADGLEY, ONE-SIXTEENTH TO OTTO J. DYCKMAN, ONE-SIXTEENTH TO WALTER G. DYCKMAN, ONE-SIXTEENTH TO SIDNEY D. McKELVEY, ONE-SIXTEENTH TO ADOLPH T. HAMMERSCHMIDT, AND ONE-SIXTEENTH TO HENRY R. DYCKMAN, ALL OF FULLERTON, CALIFORNIA.

AUTOMATIC TRAIN-STOPPING DEVICE.

1,211,720.

Specification of Letters Patent.

Patented Jan. 9, 1917.

Application filed September 25, 1915. Serial No. 52,605.

To all whom it may concern:

Be it known that I, HARRY LANDRETH, a citizen of the United States, residing at Fullerton, in the county of Orange, State of California, have invented certain new and useful Improvements in Automatic Train-Stopping Devices; and I do hereby declare the following to be a full, clear, and exact description of the invention, such as will 5 enable others skilled in the art to which it appertains to make and use the same.

This invention relates to an automatic train stopping device.

An object of the invention resides in the 15 provision of a device by means of which collisions of railroad trains will be prevented.

A further object of the invention resides in so constructing the device that the air 20 brakes will be applied gradually so as to avoid the jar incident to a sudden stopping of the train.

A further object of the invention resides 25 in so constructing the device that if a train is either running or standing in one block and a second train approaches from another block the trains will be stopped and therefore prevented from colliding.

A further object of the invention resides 30 in the provision of means for informing the engineer of the fact that a train is in the block ahead and that his train is about to be stopped so that he may shut off the steam.

With these and other objects in view, such 35 as will appear as the description progresses, the invention comprises the combination and arrangement of parts as set forth in and falling within the scope of the appended claims.

In the drawings:—Figure 1 is an elevational 40 view of the portion of the device carried by the car. Fig. 2 is an enlarged sectional view of the motor casing. Fig. 3 is a diagrammatic view of the wiring used in

45 the track circuits. Fig. 4 is an enlarged sectional view showing the wheel contacts on the car and the means for supporting the same. Fig. 5 is a diagrammatic view of the circuit formed when two cars approach each 50 other within a predetermined distance. Fig. 6 is a horizontal sectional view of the motor

casing. Fig. 7 is a vertical sectional view showing the actuating cam for the valve. Fig. 8 is a fragmental detail of the valve. Fig. 9 is a similar view. Fig. 10 is a detail 55 showing the manner of mounting one of the contact rollers. Fig. 11 is a vertical sectional view through one of the rail carrying casings. Fig. 12 is a diagrammatic view of one of the contact rails. Fig. 13 is a fragmental vertical sectional view taken in a plane parallel to the plane of Fig. 11, and Fig. 14 is a horizontal sectional view of one of the rail carrying casings.

Referring to the drawing wherein like 65 parts are indicated by like characters throughout the several views: In the embodiment of my invention shown in the drawings I have provided means for exhausting the air from the train pipe so that 70 the air brakes will be applied and this means consists of a casing 1 which is secured by suitable hangers 2 beneath a car. Located in this casing 1 is a valve 3 which has communication with the train pipe 4 through a 75 duct 5 and with the atmosphere through a duct 6. Communication between these ducts 5 and 6 is broken normally by the closing of the same by a valve plunger 7 which is pressed downwardly in its casing 8 by a coil 80 spring 9. The upper end of this valve plunger 7 is covered by a removable cap 10 secured to the casing 8. In order that this plunger 7 may be raised so as to allow the air to pass from the train pipe 4 through 85 the ducts 5 and 6 into the atmosphere I have secured to the said plunger an arm 11. Rotatably mounted in bearings 12 is a shaft 13 on the end of which is formed a cam 14 which engages the arm 11 and upon the rotation of the said shaft 15 raises the arm 11 and the plunger 7 to allow the escape of air from the train pipe as previously described. In order that this shaft 13 may be actuated I have secured to the end opposite to that on 90 which the cam 14 is secured, a worm gear 16 which meshes with a worm 17, which worm is formed on a shaft 18 supported in bearing members 19 for rotation. Secured to this shaft 18 between the bearing members 19 is 95 a gear 20 which meshes with a smaller gear 21. A gear 21' is mounted on the armature

shaft 22 of a motor 23 and meshes with the gear 21. Thus it will be seen that when the motor 23 is energized the cam 14 will raise the plunger 7 intermittently and allow the 5 air to escape through the duct 6. Communicating with this duct 6 is a pipe 24 which extends to the cab of the locomotive and is provided with a suitable whistle 25 so that the exhausting air will blow the whistle and 10 notify the engineer of the danger ahead.

Secured to the end of the casing 1 opposite to that on which the valve 3 is secured is a pipe 26 which is supported by suitable hangers and has a hollow rod 27 slidably 15 mounted therein on the end of which is a bracket 28 having a roller 29 between the legs thereof. This roller is normally pressed away from the pipe 26 and into engagement with a metallic band 30 on the inside of the 20 adjacent car wheel by a coil spring 31. It must be here stated that the car wheel which is indicated by 32 on the drawings should be made of papier mâché.

A conducting wire 32' is connected to the 25 motor 23 and to the roller 29 and extends through the pipe 26 and the rod 27. A second wire 33 is connected to the motor, extends through the pipe 26 and the rod 27 and is suitably connected to a metallic roller 34 which is mounted on a bracket 35 supported by the car sill 36. This roller 34 is normally pressed downwardly into engagement with the metallic flange 37 on the wheel 32 by a coil spring 38. In order that 35 these rollers 29 and 34 may be included in an electrical circuit at the proper times so as to energize the motor 23 and cause the intermittent closing of the valve 3 I have provided the following mechanism:

40 Arranged adjacent one of the rails indicated by the reference character 39 is a series of casings 40, each casing being located in actual practice at a distance substantially three-hundred feet from the next adjacent 45 casing. Extending longitudinally of each of these casings 40 is a channel 41 which is backed by a strip 42 secured to flanges 43 by suitable means. Slidably mounted at a plurality of points in each of these casings 50 40 are rods 43' which extend outwardly through the channel 41 and have a rail 44 secured thereto. This rail is provided at its ends with outwardly turned portions 45 and the body of the rail is pushed normally to 55 the position adjacent to the wheel rail 39 by a plurality of springs 46 which encircle the rods 43'. The inward movement of this rail is limited by the contacting of an adjustable nut 47 on each of the rods 43' with 60 the rear face of the casing 40. The distance between the rail 44 and the wheel rail 44' is slightly less than the width of the wheel flange for a purpose which will later appear.

Secured to the rail 44 between each of the 65 rods 43' and extending toward each casing

40 is a switch blade 48 which is adapted to enter between the blades 49 in each casing upon the movement of the rail 44 toward the casing.

Connected to each of the blades 49 is a 70 wire 50 which is connected to one pole of a suitable source of supply, preferably batteries. These wires 50 extend through a pipe 51 which extends parallel with the rail 44 between it and the casing 40. 75

Mounted between the casing 40 and the wheel rail of the track is a bar 52, which is clearly shown in Fig. 1 of the drawings, which bar is provided with a switch blade 53. Mounted upon the base of the rail is 80 a plate 54 which is provided with switch blades 55 between which the blade 53 is adapted to extend. The plate 54 and the bar 52 are provided with a plurality of these switch blades. The switch blades 53 are connected to the wheel rail by a wire 56 while the blades 55 are connected to the wire 50. The bar 52 is adapted to be engaged by the metallic rim 37 of the wheel 32. The mechanism on the car and on the track is duplicated on the opposite side of the car as shown in Fig. 1 of the drawings and on the opposite rail of the track.

When two trains approach within a predetermined distance of each other a circuit 95 is formed, see Fig. 5, from a battery 58 through the wire 50 to the rail 44, through the rail 44 to the band 30 on the wheel 32, to the contact roller 29 through the wire 32', through the motor 21', through the wire 33, 100 through the roller 34, through the metallic rim 37 to the wheel rail, through the wheel rail to the metallic rim on the wheel of the other car which is indicated by the reference character 59, through the said rim to 105 the bar 52, through the bar 52 and switch plates 53 and 55 and back through the wire 50 to the battery 58. Thus the motor will be energized.

In Fig. 3 of the drawings I have illustrated the rails of a track which include a plurality of sections 60 which are insulated from each other by suitable material 61. The parts which have been previously described are indicated by the reference characters by which they were designated, in this Fig. 3. It will be noted that the wiring system is divided into blocks and each section 60 of the rails has a complete system. It will also be noted that these complete systems are arranged so as to overlap each other and thus insure the stopping of trains when they are predetermined distances apart irrespective of their positions in the blocks.

110 While I have illustrated and described a particular embodiment of my invention it has merely been for the sake of convenience and I do not wish to be limited to that particular embodiment as it is obvious that nu- 115 120 125 130

merous changes may be made in the details of construction without departing from the spirit of the invention or without exceeding the scope of the claims.

5. What I claim is:—

1. In a train stopping device adapted to be mounted on a car having an air brake system therein, a valve connected to said air brake system, a motor for opening and closing said valve, an electrical circuit including one wall of the car, the rail on which the wheel operates and a supplemental resiliently mounted rail adjacent the wheel rail, means for pressing the supplemental rail 10 toward the wheel rail so that when the wheel passes between the wheel rail and the supplemental rail the circuit will be completed and the valve opened.
2. In an automatic train stopping device, means for causing the application of the air brakes, and means for controlling the said first mentioned means including a plurality of resiliently mounted electrically energized rails in spaced relation to the wheel rail, the said means being operative when the 15
- 20
- 25

flange of a wheel of a train is interposed between the wheel rail and one of the energized rails and the flange of a wheel of another train enters between another of the energized rails and the wheel rail.

30

3. In a train stopping device, the combination with the train pipe, of an air brake system, of a valve for releasing the air therefrom, means for operating said valve to open the same, the said means being included in an electric circuit, said circuit including an energized rail and a wheel rail, resilient means for maintaining the energized rail in slight spaced relation to the wheel rail so that when the flange of a wheel enters 40 between the other rail and the energized rail it will contact with each and the circuit will be completed.

35

In testimony whereof, I affix my signature, in the presence of two witnesses.

HARRY LANDRETH.
